Primary Examiner — George D. Kirschbaum*Assistant Examiner* — Lillian Windham(74) *Attorney, Agent, or Firm* — Duane Morris LLP(57) **CLAIM**

We claim the ornamental design for a test box, as shown and described.

DESCRIPTION

FIG. 1 is an exploded perspective view of a test box showing our new design.

FIG. 2 is a front elevational view of the test box.

FIG. 3 is a rear elevational view of the test box.

FIG. 4 is an exploded right side elevational view of the test box.

FIG. 5 is an exploded left side elevational view of the test box.

FIG. 6 is an exploded top plan view of the test box.

FIG. 7 is an exploded bottom plan view of the test box; and, FIG. 8 is a perspective view of the test box with the front door in an alternate position.

The broken lines in the drawings are included for the purpose of illustrating portions of the test box and form no part of the claimed design.
